UNITED STATES PATENT OFFICE.

EDWARD KNAUSS, OF MOUNT VERNON, NEW YORK, ASSIGNOR, BY DIRECT AND MESNE ASSIGNMENTS, TO THE K. P. MANUFACTURING COMPANY, INC., OF NEW YORK, N. Y., A CORPORATION OF NEW YORK.

CARBURETER.

1,212,505.

Specification of Letters Patent.

Patented Jan. 16, 1917.

Application filed June 16, 1915, Serial No. 34,502. Renewed June 9, 1916. Serial No. 102,791.

To all whom it may concern:

Be it known that I, EDWARD KNAUSS, a citizen of the United States, residing at Mount Vernon, in the county of Westchester and State of New York, have invented certain new and useful Improvements in Carbureters; and I do hereby declare the following to be a full, clear, and exact description of the invention, such as will enable others skilled in the art to which it appertains to make and use the same.

This invention relates to carbureters especially adapted for use in connection with automobile engines, and has for its object to provide an apparatus of this nature which will be simple in construction, comparatively inexpensive to manufacture, and which will be more efficient in use than those heretofore proposed.

With these and other objects in view, the invention consists in the novel details of construction and combinations of parts more fully hereinafter disclosed, and particularly pointed out in the claims.

Referring to the accompanying drawings, forming a part of this specification, in which like numerals designate like parts in all the views, Figure 1 is a diagrammatic sectional view of a carbureter and its associated parts made in accordance with this invention; Fig. 2 is a sectional view taken on the line 2—2 of Fig. 1, looking in the direction of the arrows; Fig. 3 is a detached perspective view of the Venturi tube or air regulator; and Fig. 4 is a partly sectional view of a slightly modified form of the apparatus.

1 indicates any suitable container for gasoline, kerosene, etc., provided with a float or other controller 2, coacting with the pivoted levers 3, governing the valve 4, controlling the fuel supply 5. Leading from the container 1 is the fuel passage 6, entering the atomizing nozzle 7 having the inwardly tapering nozzle end 8. Inside the pipe or nozzle 7, and preferably extending up into the inwardly tapering nozzle end 8 is the inwardly tapered end of air nozzle 9, leaving an annular chamber 10 adjustable as to its dimensions between its outer wall and the inner walls of the pipe 7 and nozzle 8. Joined to the air nozzle 9 is the screw threaded coupling member 11, adapted to adjust up and down said nozzle 9, and joined to said coupling member is the air

pipe 12, leading to the chamber 13, provided with the check valve 14; and joined to the hand operated or other pump 15 conveniently located on the dash board 16.

17 is an exhaust pipe or connection leading to the inlet manifold of the engine, not shown, and provided with the usual throttle or other valve 18. Inside the pipe 17 and surrounding the nozzle 7, is the regulator or "Venturi" tube 20, provided with the upwardly flaring inner surface 21 normally 55 mainly located above the nozzle 7, and provided with the reversely or downwardly flaring surface 22 normally surrounding said nozzle 7.

23 represents the annular inwardly projecting surface constituting the juncture between the said oppositely flared surface 21 and 70 22, which serves to restrict the annular space 24 between the surface 22 and the outer surface of the nozzle 7. The said space 75 24 opens into the chamber 25, with which the carbureter support 26 is provided, and connected with said chamber 25 is the flue or pipe 27 leading to or near the exhaust pipe or to any convenient point for supplying heated air to said chamber 25. A valve 28 controls the flue 27.

The Venturi tube or regulator 20 is provided with an outer cylindrical member 30, providing an annular space 31 between it 85 and the inner member 32. A plurality of perforations 33, are provided in the connection 34 between the two members 30 and 32, and said perforations thus connect said space 31 with the space or exhausted chamber 35 in the pipe 17. The lower end of the member 32 of the Venturi tube or regulator 20 is provided with a plurality of notched members 36 having the upwardly converging spaces 37 between them, and the 90 regulating ring 39 surrounds said lower end of the member 32 as shown. Upon this ring rests the lower edge of the member 30, so that when the ring is raised the whole regulator 20 is raised. The lower end of the tube 100 17 is screw threaded and slotted as shown, and fitting said screw threads is the external ring 40, while the pins 41 pass through the slots and connect the two rings 39 and 40.

As shown in the drawings the outer ring 105 40 is internally slotted and the outer ends of the pins 41 fit or terminate at the bot-

tom of this last named slot. This said slot extends 360° around the ring 40, so that said ring may turn freely on the screw threads with which the lower end of the tube 17 is provided, and at the same time raise and lower the pins 41 and inner ring 39. The pins 41 are conveniently located in their operative positions by boring holes, not shown, radially through the outer ring 40, slipping said pins into place and then plugging the holes.

The operation of the carbureter is as follows: The valve 4 and float 2 is so regulated as to maintain a supply of oil, or gasoline, at or near the upper end of the adjustable air nozzle 9, the same being in the form of a thin film occupying the adjustable annular space or chamber 10 between the nozzles. Air being now forced, or sucked 20 through the nozzle 9, a vacuum will be created, above said thin film and the latter will be drawn in a finely divided condition up through the converging portion 8 of the nozzle 7, and then suddenly expanded in the 25 space 90 formed by the flaring portion 21 of the regulator 20. When said space 90 in nozzle 20 is reached, the finely divided and expanding mixture of air and oil is subjected to the annular film of warm air passing 30 or sucked through pipe 27, chamber 25, space 24, past the constricting surface 23, and into said flaring space 90 in the upper end of regulator 20. This last named film or jet of air still further finely divides the 35 oil or gasoline mixture before it leaves said regulator 20, and enters the pipe 17. When this last named pipe is reached, the regulator will have been slightly raised from its seat on the ring 39, since it is slidingly fitted 40 in the exhaust pipe or tube 17, and the V shaped spaces 37 will have uncovered or have risen above said ring 39, thus admitting a greater or less quantity of air into the space 31, which will pass out of the 45 holes 33 into said pipe 17, and still further aid in subdividing said oil or gasoline. The outer surface of the upper end of nozzle 7 is inwardly tapered as shown, so that as the restricting surface 23 rises, the volume of 50 air passing the same greatly increases, and consequently the pressure of the air on the regulator 20 that is sucked through the openings 33 decreases. That is to say, the pressure on the surface 23 is first a maximum 55 so that the regulator 20 will rapidly rise to admit more air to the exhaust pipe 17. But as soon as the surface 23 separates from the outer tapered surface of the nozzle 8 this pressure rapidly falls, while the passage of 60 air through the notches 37 into the annular chamber 31 and through the perforations 33, tends to keep the regulator 20 lifted until the passage between the surface 23 and outer surface of the nozzle 8 becomes so great that 65 said regulator 20 will fall by gravity, be

again lifted by the combined pressures acting upon it. In other words the regulator 20 will rise and fall automatically thus causing a regulated quantity of air to pass into the fuel mixture, which quantity will increase and decrease with the vacuum in pipe 17, or with the speed of the motor, and thereby insure the proper amount of oxygen at 70 all times.

In order to regulate the minimum supply 75 of air through the carbureter, the ring 40 may be screwed up or down, thereby varying the position of the restricting surface 23 as well as of the V shaped spaces 37.

Under ordinary conditions of running, 80 the vacuum in pipe 17 will be sufficient to suck air through the nozzle 9 and past the valve 14, but this valve may be adjusted to permit this only after a certain speed is reached, and if so desired.

An important feature of the invention resides in the ability of priming the engine by forcing air, by means of the pump 15, through nozzle 9, and thereby filling the pipe 17 with a fuel mixture when the engine 90 is not running.

60 represents an adjustable stop for limiting the upward movement of the regulator 20, and 61 friction material for preventing fluttering of the regulator 20.

In the modified form of the invention shown in Fig. 4, the same parts are lettered with the same numerals but the flue or pipe 27, the support 26 of the carbureter and the Venturi tube or regulator 20 are somewhat 100 changed. That is to say the support 65 for the carbureter is shaped as shown, the flue 27 and valve 28 are raised somewhat and the Venturi tube or regulator 66 is provided with the perforated ring member 67 having 105 the orifices 68, so that when the said regulator descends more or less air is trapped in the chamber 69, formed by the said ring 67 and the turned in end 70 of the exhaust tube 17.

Instead of regulating the flow of air as disclosed in connection with Fig. 1, the tube 17 is made adjustable relatively to the supporting member 65 by means of the rack 71 and pinion 72, and the said tube 17 is 115 provided with a plurality of orifices 73 arranged in a spiral path as shown and which are adapted to be uncovered one at a time by the upper perforated ring member 74 of the regulator 66. The said regulator 66 120 in this form of the invention is not provided with the V shaped orifices 37, but the lower end 75 of said regulator is cylindrical in shape and the air from the flue 27 passes up through the space 24 without being able 125 to escape through the orifices 33. On the other hand, another portion of air is sucked through the orifices 73, into the space 77 between the rings 67, and 74 when the said regulator 66 rises.

It will thus be seen in both forms of the invention as the pistons of the motor are operated, a vacuum will be formed in the exhaust pipe 17, and the regulator 20 or 66 will cause a proper proportion of air to be drawn in to mix with the adjustable quantity of gasolene supplied from the container 1 under atmospheric pressure. It will also be observed that the gasolene is fed in a thin hollow circular film, which surrounds a cylindrical jet of air, and that therefore a very fine subdivision of the gasolene and a very thorough mixture with air is had, which is further enhanced by other air jets 15 at a high velocity.

It will likewise be seen that by using the hand pump 15 for priming purposes, the motor can be readily started in zero weather.

It is obvious that those skilled in the art may vary the details of construction as well as the arrangement of parts without departing from the spirit of my invention and therefore, I do not wish to be limited to the above disclosure, except as may be required by the claims.

What I claim is:—

1. In a carbureter the combination of a fuel supply; inner and outer concentric nozzles providing an annular space between them, said outer nozzle being outwardly tapered; connections between said supply and said annular space; hand operated means adapted to be located on the dashboard of a vehicle to cause air to pass through said inner nozzle and to suck fuel out of said space; a second air supply; and adjustable sliding automatic means reversely tapered on its inside surrounding said outwardly tapered nozzle for controlling said second supply, substantially as described.

2. In a carbureter the combination of a fuel supply; inner and outer concentric nozzles providing an annular space between them; connections between said supply and said annular space; an automatic regulator provided with inner and outer walls spaced apart to provide an annular space between them open at its bottom, and with a chamber surrounding the delivery ends of said nozzles forming an annular passage outside of said outer nozzle; means to cause air to pass through said inner nozzle and annular passage and to suck fuel out of said space; means for adjusting said regulator to vary said passage, and means to permit air to enter said second named annular space substantially as described.

3. In a carbureter the combination of a

fuel supply; inner and outer concentric nozzles having a space between them; a connection between said space and said supply; an exhaust pipe in which said nozzles are located; and an automatic regulator in said exhaust pipe surrounding said nozzles and slidably movable in said pipe, said regulator provided with an annular chamber and a plurality of perforations leading to said chamber; and means controlling the admission of air to said chamber, substantially as described.

4. In a carbureter the combination of a fuel supply; inner and outer nozzles connected with said supply and adapted to hold a thin film of fuel between them; said outer nozzle having an outer tapered surface; an exhaust pipe in which said nozzles are located; a slideable automatic regulator provided with a restricting surface surrounding said nozzles and located in said exhaust pipe; an air supply connected to said regulator; and an additional air supply connected to said inner nozzle, substantially as described.

5. In a carbureter the combination of a fuel supply; inner and outer nozzles connected with said supply and adapted to hold a thin film of fuel between them; said outer nozzle having an outer tapered surface; an exhaust pipe in which said nozzles are located; a slideable automatic regulator having upwardly and downwardly flaring inner surfaces, said regulator also provided with a restricting surface surrounding said nozzles and located in said exhaust pipe; an air supply connected to said regulator; an additional air supply connected to said inner nozzle; and means to adjust said regulator up and down to predetermined positions substantially as described.

6. In a carbureter the combination of a fuel supply; inner and outer nozzles connected with said supply and adapted to hold a thin film of fuel between them; an exhaust pipe in which said nozzles are located; a slideable regulator provided with a restricting surface surrounding said nozzles and located in said exhaust pipe; means for adjusting said regulator up and down to predetermined positions; an air supply connected to said regulator; and an additional air supply connected to said inner nozzle; substantially as described.

In testimony whereof I affix my signature, in presence of two witnesses.

EDWARD KNAUSS.
